(57) **CLAIM**

The ornamental design for a display stabilizer, as shown and described.

DESCRIPTION

FIG. 1 is a perspective view of a first variant of the display stabilizer.

FIG. 2 is a front view of the display stabilizer of FIG. 1.

FIG. 3 is a rear view of the display stabilizer of FIG. 1. FIG. 4 is a left side view of the display stabilizer of FIG. 1. FIG. 5 is a right side view of the display stabilizer of FIG. 1.

FIG. 6 is a top view of the display stabilizer of FIG. 1. FIG. 7 is a bottom view of the display stabilizer of FIG. 1. FIG. 8 is a perspective view of the display stabilizer of FIG. 1, shown in an environment of use.

FIG. 9 is a perspective view of a second variant of the display stabilizer.

FIG. 10 is a front view of the display stabilizer of FIG. 9. FIG. 11 is a rear view of the display stabilizer of FIG. 9. FIG. 12 is a left side view of the display stabilizer of FIG. 9.

FIG. 13 is a right side view of the display stabilizer of FIG. 9.

FIG. 14 is a top view of the display stabilizer of FIG. 9. FIG. 15 is a bottom view of the display stabilizer of FIG. 9. FIG. 16 is a perspective view of the display stabilizer of FIG. 9, shown in an environment of use.

FIG. 17 is a perspective view of a third variant of the display stabilizer.

FIG. 18 is a front view of the display stabilizer of FIG. 17. FIG. 19 is a rear view of the display stabilizer of FIG. 17. FIG. 20 is a left side view of the display stabilizer of FIG. 17.

FIG. 21 is a right side view of the display stabilizer of FIG. 17.

FIG. 22 is a top view of the display stabilizer of FIG. 17. FIG. 23 is a bottom view of the display stabilizer of FIG. 17. FIG. 24 is a perspective view of the display stabilizer of FIG. 17, shown in an environment of use.

FIG. 25 is a perspective view of a fourth variant of the display stabilizer.

FIG. 26 is a front view of the display stabilizer of FIG. 25. FIG. 27 is a rear view of the display stabilizer of FIG. 25. FIG. 28 is a left side view of the display stabilizer of FIG. 25.

FIG. 29 is a right side view of the display stabilizer of FIG. 25.

FIG. 30 is a top view of the display stabilizer of FIG. 25. FIG. 31 is a bottom view of the display stabilizer of FIG. 25; and,

(Continued)

FIG. 32 is a perspective view of the display stabilizer of FIG. 25, shown in an environment of use. The broken lines represent portions of the display stabilizer that form no part of the claimed design.
